HOMER HASTING, OF DETROIT, MICHIGAN

AIR PUMP

Application filed May 23, 1929. Serial No. 365,252.

The present invention pertains to a novel fluid pump, particularly referring to that type of pump adapted for inflating pneumatic tires.

5 The primary object of the present invention is to devise a double acting air pump which forces air into the tire on both the upward and downward strokes, the pump being constructed to have no outwardly projecting air inlet members which might easily be broken nor having any ball checked inlets subject to disorder. The pump is formed with a single compression cylinder in which is reciprocated a double acting piston, the pump being provided with a single air inlet automatically controlled which permits both the upward and downward strokes of the double-acting piston to compress the air and force it out of a single outlet which is 15 also automatically controlled to lead the pressures from both sides of the piston into a pneumatic tire.

Another object of the present invention is to provide a double acting fluid pump which 20 is of simple construction, having a simple and efficient valve mechanism controlling the air inlet which is arranged remote from the ground and thereby avoids the possibility of dirt or grit entering the valve mechanism 25 and preventing the pump to properly function.

With these and other objects in view the invention consists in matters hereinafter set forth and more particularly pointed out in 30 the appended claims, reference being had to the accompanying drawings, in which

Figure 1 is a side elevation of a fluid pump constructed in accordance with the present invention;

40 Figure 2 is a vertical cross sectional view of the pump, illustrating the compression piston nearing the bottom of its pressure stroke with the inlet and outlet valve mechanisms in 45 a position corresponding;

Figure 3 is a fragmentary vertical cross sectional view illustrating the compression piston beginning its upward compression stroke with the inlet and outlet valve mechanism in a position corresponding;

Figure 4 is a transverse cross sectional view taken on the line 4-4 of Figure 2;

Figure 5 is a detail side elevation of the inlet controlling sleeve valve, and

Figure 6 is a fragmentary detail of the 55 lower end of the air inlet over which the valve sleeve slides.

Like characters are employed throughout to designate corresponding parts.

The present pump comprises a barrel or 60 cylinder 1 having a cap 2 screwthreaded upon the upper end thereof and having a base member 3 screwthreaded upon the lower end, the base member being provided with a foot-piece 4. A tube 5 is brazed to the cylinder 1 65 as at 6 and is bent downwardly so that the axis thereof is parallel with the axis of the cylinder 1, the tube 7 being similarly brazed at 8 and bent to extend upwardly and lie parallel to the cylinder 1. Over the ends of these 70 tubes 5 and 7 is placed a surrounding tube 9 provided with an outlet member 10 upon which is mounted an air pressure gauge 11, the tube 9 extending a considerable distance 75 over the ends of the tubes 5 and 7 which gives an effective air seal. The ends of the tubes 5 and 7 are spaced from each other and the surrounding tube 10 thereby forms a cylinder 12 in which is placed a piston 13, the function of which will become apparent as 80 the description progresses.

An elongated tube 14 extends through the cap 2 into the cylinder 1, the cap having suitable packing 15, held in place by a nut 16 to prevent leakage of air around the tube 85 and to permit longitudinal movement thereof. The end of the tube 14 which extends outside the cylinder 1 is provided with a handle 17 for the purpose of imparting longitudinal movement to the tube which is to 90 serve as a piston rod or plunger.

The lower end of the tube 14 is plugged at 18 and is provided with a key 19 which extends through the tube to project outwardly, the tube having two ports 20 and 21 positioned between the plug 18 and the key 19. A sleeve 22 is mounted over the lower end of the tube 14 and is provided with a slot 23 into which projects the key 19, the sleeve being adapted to slide longitudinally, 100

the length of the longitudinal movement being limited by flanges on the plug 18 and by the key 19. The sleeve 22 is provided with ports 24 and 25 which register with the 5 ports 20 and 21 in a manner presently to be described. The sleeve 22 is further provided with a screwthreaded portion which supports a double acting piston 26.

It will be observed from the description 10 that the piston 26 is mounted upon the sleeve 22 which is slidable on the tube 14, the purpose and function of which will now be described. As illustrated in Figure 2 the piston is being forced downwardly and the air 15 pressure below the piston causes the latter to move the sleeve 22 upwardly until the key 19 engages the end of the slot 23 at which time the port 20 in the tube 14 registers with the port 24 in the sleeve 22 and thereby leaves 20 an open passage between the space in the cylinder above the piston 26 to the atmosphere and permits air to enter to fill the space which otherwise would create a vacuum. The air being compressed below the 25 piston 26 is forced into the tube 7 and exerts pressure on the piston causing it to rise and seat against the lower end of the tube 5 and thereby permits the compressed air to go into the line 10. The movement of the piston 13 30 is assisted by the suction on the upper side of the piston which will also cause suction in the tube 5 when the piston 26 is forced downwardly.

When the piston 26 has completed its 35 downward motion and is being drawn upwardly the pressure on the upper side of the piston 26 causes the slideable sleeve 22 to move downwardly upon the stem 14 until the end butts against the flanges on the plug 18. In 40 this position the port 22 in the tube 14 is in registration with the port 25 in the sleeve and air is thereby admitted to the lower side of the piston 26 through the tube 14. The air is compressed above the piston 26 and is 45 forced into the tube 5, causing the piston 13 to seat upon the upper end of the tube 7 and permitting the pressure to enter the line 10.

The valve ports in the tube 14 and the 50 sleeve 22 are so positioned that it is impossible for the ports 20 and 24 to be in registration when the ports 21 and 25 are in registration. The piston 26 in being mounted in this manner may be utilized to operate the 55 valve mechanism which thereby becomes entirely automatic, requiring no springs or parts which are liable to become disordered.

Upon the top of the piston actuating tube 14 where it projects above the handle 17 is 60 provided a nut 27 to which may be attached a hose line (not shown) which is in connection with a tank or any other member and by reciprocating the piston the air or fluid may be pumped out of the tank or other 65 member. It therefore becomes apparent

that the pump may be utilized as a source of forcing air into a receptacle or it may be utilized to pump the air out of a receptacle.

Although a specific embodiment of the present invention has been illustrated and 70 described, it will be understood that changes may be made within the scope of the appended claims without departing from the spirit of the invention and such changes are contemplated.

What I claim is:

1. A double acting fluid pump comprising a cylinder having valve controlled outlets at each end thereof, a tube extending into said cylinder and having spaced perforations in the lower end thereof, a plug for closing the lower end of said tube, a sleeve slidably mounted on the lower end of said tube and provided with perforations spaced closer together than the perforations in said tube and limited in sliding movement in one direction by said plug, a double acting piston mounted on said sleeve between the perforations therein, said piston being adapted to create a pressure and force air out one of said outlets when reciprocated upwardly or downwardly in said cylinder and to create a partial vacuum in the cylinder on the opposite side of the piston, and means for limiting the sliding movement of said sleeve so that the perforation in said sleeve on the partial vacuum side of said piston is in registration with a perforation in said tube to supply air at atmospheric pressure through said tube to relieve the partial vacuum, said means comprising slots formed in the upper end of said sleeve, and a key carried by said tube to project into said slots to prevent rotary movement and limit the longitudinal movement of said sleeve.

2. A double acting fluid pump comprising a cylinder having valve controlled outlets at each end thereof, a tube extending into said cylinder and having spaced perforations in the lower end thereof, a headed plug for closing the lower end of said tube, a sleeve slidably mounted on the lower end of said tube and provided with perforations spaced closer together than the perforations in said tube and limited in sliding movement by said head plug, a double acting piston mounted on said sleeve between the perforations therein, means for limiting the sliding movement of said sleeve on said tube so that reciprocation of said tube causes reciprocation of said piston and causes pressure in said cylinder upon both the upward and downward strokes of said piston, said limiting means comprising slots formed in the upper end of said sleeve, and a key carried by said tube to project into said slots in a manner preventing rotary movement of said sleeve and causing the perforation in said sleeve on the suction side of said piston to register with a perforation in said tube.

3. A double acting fluid pump comprising a cylinder having valve controlled outlets at each end thereof, a tube extending into said cylinder and having spaced perforations in the lower end thereof, a headed plug for closing the lower end of said tube, a sleeve slidably mounted on the lower end of said tube and provided with perforations spaced closer together than the perforations in said tube and limited in sliding movement by said head plug, a double acting piston mounted on said sleeve between the perforations therein, means for limiting the sliding movement of said sleeve on said tube so that reciprocation of said tube causes reciprocation of said piston and causes pressure in said cylinder upon both the upward and downward strokes of said piston, said limiting means comprising slots formed in the upper end of said sleeve, and a key carried by said tube to project into said slots in a manner preventing rotary movement of said sleeve and causing the perforations in said sleeve on the suction side of said piston to register with a perforation in said tube, and said sleeve closing the opening in said tube on the pressure side of said piston.

In testimony whereof I affix my signature.
HOMER HASTING.
